UNITED STATES PATENT OFFICE.

ELIAS BUEGELEISEN, OF BROOKLYN, NEW YORK, ASSIGNOR OF ONE-HALF TO LEO STRAUSS, OF ARVERNE, NEW YORK.

DEVICE FOR MANICURING AND OTHER PURPOSES.

1,182,247.

Specification of Letters Patent.

Patented May 9, 1916.

Application filed February 1, 1916. Serial No. 75,556.

To all whom it may concern:

Be it known that I, ELIAS BUEGELEISEN, a citizen of the United States, residing at 1061 Fifty-sixth street, borough of Brooklyn, county of Kings, State of New York, have invented certain new and useful Improvements in Devices for Manicuring and other Purposes, of which the following is a specification.

10 This invention relates to devices for manicuring and other purposes and has for some of its objects to provide an efficient and substantial means, whereby the cutting, trimming, paring, shaping or otherwise treating 15 of nails, corns, or other substances, may be accomplished in a rapid and careful manner, and comprises the combination of co-operating members and arrangement of parts whereby new and useful results are obtained or secured, and whereby the purchase 20 of the jaw actuating member may be increased or decreased and the cutting bite more positively controlled and cutting more perfectly performed regardless of the varying 25 hardness of the substance to be cut, and whereby the scope and tension of the cutting jaws may be regulated in accordance with the selective character of the material or substance to be treated, whether it be skin 30 or nails to be shaped, trimmed, or formed, and with these and other objects in view the invention in one of its forms is illustrated in the accompanying drawing to which attention is directed in which;

35 Figure 1 is a plan view, Fig. 2 is a plan view with the sheath for nail cleaning member withdrawn, Fig. 3 is a side elevation, Fig. 4 is a cross section of the device opened and shown as in normal use, and Fig. 5 is a 40 similar view showing the augmenting means for increasing the leverage on the cutting jaws in position and increase or decrease of purchase of the cam on the movable jaw bearing or carrier.

45 Similar numerals of reference indicate corresponding parts in the various views.

Referring to the various views the numeral 20 indicates a base provided with a fixed jaw 21 at one terminus thereof, the 50 base 20 being provided with the angularly disposed members 22 and 23 providing a guide way for the movable or slidable means 24 for altering the cam bearing so as to increase the bite of the movable jaw, which

forms a terminus of the spring member 7 55 which is secured to the base 20 by the rivet 8.

The movable or slidable cam purchase altering member 24 is provided with the slot 9 which slides on the pin member 10 so that its position may be moved forward or backward 60 between the guideway angular projections 22 and 23 upon the base 20. The said slidable member 24 is provided at its inner end with a wedge shaped means 11 for the cam bearing and at its outer end with a sheath 65 12 for securing the lever 13 and protecting the nail cleaning point 14 thereof when the article is not in use. The sheath member 12 is also provided at its outer end with the parallel channels 18 for the purpose of providing a means for readily sliding or opening and closing the same by means of the finger nail. The lever 13 is provided with a pivot bearing 15 which secures it in a movable position to the angular side projections 70 22 and 23 extending from the base 20, the pivoted end being provided with the pressure cam 16 adapted to engage the spring member 7 and depress the same when pressure is applied to the lever 13. The increase 75 in leverage when desired is augmented by pushing forward the member 24 until the wedge member 11 resides at a point which will be engaged by the cam member 16 as shown in Fig. 5, thereby altering and 80 increasing the force of the bite of the jaws 21 and 6 when brought into co-action. The lever 13 is provided at its outer end 14 with the nail cleaning device and at its under side with a nail file 19. This combination of co- 85 acting means and arrangement of parts provides a device of superior compactness and utility both as an article of manufacture, and as a means of simplicity for the co-action and co-operation of the various elements 90 or members, and whereby a new and useful result including means for adjustment or increase or decrease of the bite cutting or trimming member may be controlled and regulated at will with reference to the particular character of the substance to be acted upon.

The combination of parts and co-action of members being so arranged as to present the combination in its most sanitary character 105 whereby the parts are maintained in a clean and germicidal condition through the free circulation of air to all the parts without

interruption by reason of its open character of arrangement and whereby it may be readily cleaned and dried without fear of rust or disarrangement of parts.

5 In the employment of the device the sheath 12 is first withdrawn by means of the pressure of a finger nail engaging the channels 18, upon the withdrawal of which the lever 13 is thrown up by action of the 10 spring member 7 and may be thrown back entirely or extended in a direction forward of the cutting jaws 21 and 6 when it is desired to employ the nail file 19 or the nail cleaning device 14 of the lever 13. When it 15 is desired to cut the nails all that is necessary is to place the nail between the biting jaws 21 and 6 and depress the lever 13 whereby nails or pieces of skin, such as corns and so forth may be readily cut and trimmed. 20 When however it is desired to cut a heavy nail or some substance of increased cutting resistance the sheath 12, as shown in Fig. 4, is pressed or pushed forward together with its member 24 until it rests in a position as 25 shown in Fig. 5 whereby the inner end or wedge member 11 of the member 24 is forced in a position under the inner end of the cam 16 so that upon depressing the lever 13 a superior purchase and pressure upon the 30 spring member 7 is exerted and the cutting jaws 21 and 6 brought into closer co-acting relation resulting in a sharper and greater biting or cutting capacity.

In Fig. 1 the device is shown in its closed 35 position, while in Fig. 2 it is shown with the sheath withdrawn as it would appear in the sectional view Fig. 4.

It is obvious that the shape and construction of the various members may be of any 40 selective form or character, and that the material of which it is constructed may be of any selective kind, without departing from the spirit of the invention, so long as the integrity of the combination and the 45 arrangement of parts are such as to cover and produce the desired result.

Having now described my invention what I claim is:—

1. A device for manicuring and other purposes, comprising the combination of a base 50 carrying a fixed jaw, a movable spring actuated member carrying an opposite jaw, means for securing the base to the spring actuated member, means for depressing the 55 spring actuated member and bringing the jaws in co-action, and means for altering the depressing scope of the depressing member and regulating the bite of the jaws.

2. A device for manicuring and other purposes, comprising the combination of a base 60 carrying a fixed jaw, a movable spring actuated member carrying an opposite jaw,

means for securing the base to the spring and actuated member, a lever carrying a cam for depressing the spring actuated member and bringing the jaws in co-action, and means for altering the depressing scope of the cam and regulating the bite of the jaws. 65

3. A device for manicuring and other purposes, comprising the combination of a base 70 member provided with a fixed jaw at or near one terminus, a spring actuated member communicating with the base member and extending therefrom carrying an opposite jaw, means intermediate of the termini of 75 the base member for securing the spring member, a lever carried by the base member bearing a cam capable of moving the spring bearing jaw toward the fixed jaw and releasing and separating the jaws by a rotating movement, a nail cleaning member at the terminus of the lever opposite the fulcrum and cam, means for anchoring the lever in a depressed position and housing or sheathing the point of the nail cleaning member, 80 and means for altering the depressing action of the cam actuated by the lever and regulating the closing of the jaws. 85

4. A device for manicuring and other purposes, comprising the combination of a base 90 member provided with a fixed jaw at or near one terminus, a spring actuated member communicating with the base member and extending therefrom carrying an opposite jaw, means intermediate of the termini of 95 the base member for securing the spring member, a lever carried by the base member bearing a cam capable of moving the spring bearing jaw toward the fixed jaw and releasing and separating the jaws by a rotating movement, a nail cleaning member at the terminus of the lever opposite the fulcrum and cam, means for anchoring the lever in a depressed position and housing or sheathing the point of the nail cleaning member, 100 and means for altering the depressing action of the cam actuated by the lever and regulating the closing of the jaws. 105

5. A device for manicuring and other purposes, comprising the combination of a plurality of cutting-jaws oppositely disposed, a jaw bearing means extending from each jaw and secured at a distance, spring actuated means for separating the jaw bearing 115 members, means for moving the jaws toward each other, and means for altering the bite of the jaws when in co-action.

In testimony whereof I affix my signature in presence of two witnesses.
